TWISTED STRAND

Georg Dressel, Weidhausen, Germany, assignor to
the firm "Dreia" Flechtmaterialges, m. b. H.,
Nuremberg, Germany

Application January 26, 1938, Serial No. 187,085
In Germany May 10, 1937

11 Claims. (Cl. 117—52)

The invention relates to a twisted strand for domestic and decorative articles, more particularly for wickerwork, wickerwork furniture, coal cauldrons, shell-baskets and the like.

5 The invention resides in that the twisted strand consists in a core made of vegetable or synthetic fibres and a covering made of natural or synthetic material tightly surrounding the core and forming a tight surface. The fibres forming the 10 core are, for instance, made of wood shavings, and are twisted or woven together. A band, for instance made of sheet cellulose, wound around the core, preferably in the same direction as the fibres thereof, serves as a casing and the convolutions of which partly overlap.

A guiding thread may be provided centrally in the strand. The strength of the strand as regards pull and twist may be increased by an inner member spun in the core fibres and preferably made of a yarn-like twisted or spun thread, the sense of rotation of which is preferably opposite to that of the core fibres.

The outer casing, of uniform thickness, of the twisted strand formed by the covering band 25 may, likewise be reinforced by a multiple, for instance double covering. In this form the two covering bands are twisted in opposite direction to each other. The covering band may further be reinforced by means of a thread-like strip 30 preferably arranged on the inside or between two layers thereof.

A further characteristic of the invention resides in that a thread or band-like member may be twisted around the core and beneath the covering, preferably opposite to the direction of the fibres of the core.

It is particularly advantageous to treat, for instance, by saturation, the constituents of the twisted strand prior to or during the manufacture or the twisted strand when finished with an adhesive or impregnating medium.

A twisted strand made according to the invention, in addition to being very stiff and resistant to pulling, has an increased strength against 45 kinking and twisting. The new twisted strand is reliably protected against being crushed which frequently happens with reed and cane. Nevertheless the flexibility and smoothness of the twisted strand are not impaired since the 50 siliency of the fibres of the core is neither influenced by the inner member nor by the covering wound therearound.

It is not only very waterproof and weatherproof, but has more particularly a very resistant 55 surface. No parts project outwardly not even

at sharp kinks which frequently happens in known wickerwork and in this way often causes damage to clothes and injuries. The new twisted strand may be easily manipulated and treated.

The new twisted strand further forms a tight 5 mass which by reason of the outer covering wound therearound, does not loosen unintentionally.

The invention is illustrated in the accompanying drawing, wherein:

Fig. 1 shows a portion of the novel twisted strand (with guiding thread);

Fig. 2 shows a portion of twisted strand with the core spun in the interior;

Fig. 3 shows a partly covered portion of twisted 15 strand with a thread wound therearound between core and cover;

Fig. 4 shows a portion of twisted strand with a double covering; and

Fig. 5 shows the inner side of a piece of cov- 20 ering band in plan.

The new twisted strand comprises a core *a* and a covering *b*.

The core may be made of vegetable or synthetic fibres. It is preferably made of wood shav- 25 ings, cane fibres, reed or the like.

It is particularly advantageous to spin or twist the fibres *c* of the core so tightly together that the core forms a dense mass. In addition to the strength thus produced, it is very flexible since, 30 if necessary, the individual fibres may be relatively displaced.

The covering *b* preferably consists of a band *d* wound tightly around the core *a*. The convolutions of the band *d* partly overlap so that a 35 uniform, tight and smooth surface is formed which completely covers the core *a* even at the sharpest bends. The band *d* is preferably wound around the core *a* in such a manner that its sense of rotation is opposite to that of the core 40 fibres.

The covering band *d* consists of flexible, waterproof material capable of resistance. Synthetic bands, for instance made of sheet cellulose, more particularly so-called glass skin as well as suit- 45 ably treated bands made of vegetable fibres such as impregnated bast or bands made of impregnated fabric may be used.

By means of the covering *b* the core receives a good support and a secure guide. Its flexibility 50 and strength are simultaneously increased.

In order to increase its strength against traction and kinking, a guiding thread *e* made of animal, vegetable or synthetic fibres may be arranged in the centre of the core *a*.

It is very advantageous to embody in the twisted core *a* a centre member *f*. This member not only increases the strength against traction and kinking of the strand, but, in particular, 5 protects it from the danger of becoming crushed.

A thread- or band-like centre member may be employed. It is preferable, however, to embody in the twisted fibres of the core, a thin drill or spun yarn *f*. The sense of rotation 10 thereof is opposite to that of the fibres of the core.

As shown in Fig. 3, between the core *a* and the covering *b* there may be interposed a thread- or band-like twisted covering member *g* tightly 15 surrounding the core *a* and preferably running opposite to the sense of rotation of the fibres of the core. This twisted covering member *g*, which further increases the strength of the strand and likewise protects it from being crushed, also prevents the dense mass of the core from becoming loose. In consequence of its helicoidal arrangement the twisted covering member *g* may follow the movements of the strand. It thus does not impair the flexibility thereof. The covering 20 band *d* is in this case arranged opposite to the direction of rotation of the twisted covering member *g*.

In twisted strands, the surfaces of which have to be particularly resistant, a double covering 30 may be provided. This is preferably arranged in such a manner that the two covering bands *h* and *i* are wound around the core in opposite directions. The covering is further increased by thread-like strips *k* mounted for instance on the 35 inside of the covering band or embodied therein between two layers. The reinforcing strip *k* may be made of vegetable, animal or synthetic fibres; a thin cotton thread is preferably used.

If articles are to be made from the twisted 40 strand which are likely to be subjected to particularly heavy wear or which are to have the appearance of drill material, two or more strands of the kind described may be woven or twisted together.

The resistance of the strand, more particularly 45 its insensibility to weather influences and humidity may be increased still further by treating, for instance, impregnating it, with an adhesive. A gelatine- or glue-containing liquid may, for 50 instance, be used as adhesive. The strand may also be treated with an impregnating medium. Paraffin, oils, fats, varnishes or lacquers, for instance, natural and synthetic resin lacquers may, for instance, be used. The treatment with 55 these media may be effected in such a manner that the constituent parts are saturated therewith prior to or during the manufacture, or the finished core is saturated.

The novel strand may be produced in any 60 desired color by using, instead of the translucent covering band, a colored or lacquered band. In this manner strands may be produced for decorative purposes in the brightest colors

without it being necessary to lacquer them after their manufacture is completed.

For the manufacture of domestic articles made of thin twisted strand, such as for instance for small articles of use, decorative articles, such as 5 decorative baskets, fashionable articles, hat decorations, hats and the like, as well as for toys, the core may be formed only of a single thread, for instance of a wood splint or spill which is tightly twisted to such an extent that the core 10 receives a strong structure.

The new twisted strand is particularly suitable for wickerwork, wickerwork furniture and the like. But it may also be employed for packing, as lining and covering, as fences (railings), as 15 heat protective means, for footwear (small sandals, shoes) as festoons and decorations and so on.

Having regard to the foregoing disclosure, the patent of which this specification forms part 20 confers, subject to the conditions prescribed in the Patent Act, 1935, the exclusive right, privilege and liberty of making, constructing, using and vending to others to be used, the invention 25 as defined in claims submitted by the patentee as follows.

I claim:

1. A twisted strand for woven articles such as wickerwork furniture, baskets, carriage bodies, and the like, comprising a core of at least one 30 strand of wood shavings, and a covering band wound around the core and composed of a flexible and waterproof cellulose sheet.

2. A strand according to claim 1, in which the cellulose is glass skin.

3. A strand according to claim 1, in which a guiding thread is provided centrally of the core.

4. A strand according to claim 1, in which a guiding thread is provided centrally of the core, and consisting of a yarn-like twisted thread 40 whose sense of rotation is opposite to that of the strand of wood shavings.

5. A strand according to claim 1, in which the covering band is provided with thread-like reinforcing strips.

6. A strand according to claim 1, in which the covering band is provided with thread-like reinforcing strips of vegetable fibres.

7. A strand according to claim 1, in which the covering band is provided with thread-like reinforcing strips of animal fibres.

8. A strand according to claim 1, in which the covering band is provided with thread-like reinforcing strips of synthetic fibres.

9. A strand according to claim 1, in which an intermediate covering is provided between the core and covering band in the form of a thread which is wound around the core in a direction opposite to that of the core.

10. A strand according to claim 1, in which the strand of wood shavings is woven.

11. A strand according to claim 1, in which the strand of wood shavings is twisted.

GEORG DRESSEL.
